UNITED STATES PATENT OFFICE.

SUMNER A. DUDLEY, OF TAUNTON, MASSACHUSETTS, has invented and is securing the right to a new and useful improvement in Loom-Shuttles, of which

No. 921,377, a Specification of Letters Patent. Patented May 11, 1909.

Application filed June 15, 1908. Serial No. 438,468.

To all whom it may concern:

Be it known that I, SUMNER A. DUDLEY, a citizen of the United States, residing at Taunton, in the county of Bristol and State of Massachusetts, have invented a new and useful Improvement in Loom-Shuttles, of which the following is a specification.

This invention has reference to an improvement in shuttles, and more particularly to an improvement in hand threading loom shuttles.

The object of my invention is to improve the construction of a loom shuttle, whereby the shuttle is provided with a simple, durable and inexpensive hand threading device adapted to facilitate the threading of the shuttle by hand without suction.

My invention consists in the peculiar and novel construction of the delivery end of a loom shuttle and mechanism for threading the shuttle by hand, as will be more fully set forth hereinafter and claimed.

Figure 1 is a top plan view of the thread delivery end of my improved hand threading loom shuttle. Fig. 2 is a side view of the delivery end of the shuttle looking at the delivery eye side. Fig. 3 is a longitudinal sectional view through the delivery end of the shuttle taken on line 3-3 of Fig. 1. Fig. 4 is a transverse sectional view through the shuttle taken on line 4-4 of Fig. 2 looking toward the end of the shuttle. Fig. 5 is an enlarged side view of the inner threading member, and Fig. 6 is an enlarged perspective view of the outer or guide eye member of the threading mechanism.

In the drawings, *a* indicates the thread delivery end of a loom shuttle, *b* the bobbin, *c* the bobbin cavity, *d* the throat, *e* a cavity at the end of the throat *d* extending from the top of the shuttle downward to the center of the shuttle and opening into the throat *d*, *f* a circular recess in the side of the shuttle, *g*, a round transverse hole extending centrally from the depression *f* into the cavity *e*, *h* an inclined transverse slit extending from the top and side downward toward the point to the center of the shuttle and into the circular cavity *e*, *i* a longitudinal slit extending in from the side of the shuttle to the cavity *e* and intersecting the slit *h* and the hole *g* and forming with the slit *h* a wedge-shaped projection *k*, *l* a small off-center vertical hole extending downward from the bottom of the cavity *e*, *m* a small transverse hole extending

inward from the circular recess *f* under the hole *g*, *n* the inner threading member, and *o* the guide eye member of the threading mechanism.

The inner threading member *n* is formed of wire shaped to have the straight shank 7 and the pointed end 8 bent at right angles to the shank, as shown in Fig. 5. The shank 7 is driven downward into the small hole *l* in the bottom of the cavity *e* and the pointed end 8 forced into the wedge-shaped projection *k*, as shown in Figs. 3 and 4. The guide eye member *o* is formed from wire shaped to have the straight shank 9 and the circular coiled end 10 bent at right angles to the shank and having the reduced end 11 slightly clearing the base of the coil and forming an opening 12 between the end 11 and the base of the coil, as shown in Figs. 2 and 6. The shank 9 is driven into the small transverse hole *m* in a position to bring the coiled end 10 into the circular depression *f*, as shown in Figs. 2 and 4.

In threading the shuttle the thread is first pulled from the bobbin *b* over the cavity *e* and depressed into the cavity *e*, then carried into and through the slit *h* into the slit *i*, and then through the slit *i* into the depression *f* from which point it is carried under the reduced end 11 and through the opening 12 into the coiled end 10 of the guide eye member *o* which forms the delivery eye of the shuttle. The thread now runs from the bobbin *b* around the inner threading member *n* through the slit *i* and hole *g* and out through the coiled end 10 of the guide eye member *o*. The thread is now prevented from returning by the lower edge of the circular depression *f* holding the thread away from the opening *l* in the guide eye member *o*.

Having thus fully described my invention, I claim as new and desire to secure by Letters Patent:

1. A shuttle body having a cavity at the end of the throat, a transverse hole extending in and from the side to the cavity, a thread passage in the form of a slit extending from the top and side downward at an angle and then back longitudinally into the cavity and transverse hole, an inner threading member having a straight shank driven downward into the bottom of the cavity and a pointed end forced into the wall of the cavity, and a guide eye member in the transverse hole in the shuttle.

2. A shuttle body having a cavity at the end of the throat extending from the top of the shuttle downward, a transverse hole extending from the side of the shuttle inwardly 5 to the cavity, a thread passage in the form of a slit extending from the top and side downward at an angle toward the point of the shuttle and into the cavity and then back longitudinally toward and into the cavity 10 and transverse hole, forming a wedge-shaped projection in the wall of the cavity, an inner threading member having a straight shank driven downward into the bottom of the cavity, and a pointed end bent at right angles 15 and forced into the wedge-shaped projection, and a guide eye member in the transverse hole in the shuttle.

3. A shuttle body having a cavity at the end of the throat extending from the top of 20 the shuttle downward, a circular recess in the side of the shuttle, a transverse hole extending from the recess into the cavity, a thread passage in the form of a slit extending from the top and side downward at an angle into 25 the cavity and toward the point of the shuttle and then back longitudinally toward and into the cavity, the recess and the transverse hole, forming a wedge-shaped projection in the wall of the cavity, an inner threading 30 member having a straight shank driven into the bottom of the cavity and a pointed end bent at right angles and forced into the wedge-shaped projection, and a guide eye member having a straight shank and a coiled 35 end bent at right angles and secured by driving the shank into the transverse hole in the shuttle in a position to bring the coiled end

into the circular recess in the side of the shuttle.

4. The combination with a shuttle body 40 having a bobbin cavity *c*, a throat *d*, a cavity *e* at the end of the throat *d*, a circular recess *f* in the side, a transverse hole *g* extending from the recess *f* the cavity *e*, an inclined slit *h* extending from the top and side downward toward the point of the shuttle and into the cavity *e*, a longitudinal slit *i* extending in from the side of the shuttle to the cavity *e* and intersecting the slit *h* and the hole *g* and forming with the slit *h* a wedge-shaped 45 projection *k*, a small off-center vertical hole *l* extending downward from the bottom of the cavity *e*, and a small transverse hole *m* extending inward from the recess *f* under the hole *g*, of an inner threading member *n* having the shank 7 adapted to be driven into the vertical hole *l* and a pointed end 8 bent at right angles and adapted to be forced into the wedge-shaped projection *k* and a guide eye member *o* having the shank 9 adapted 50 to be driven into the transverse hole *m*, and a coiled end 10 bent at right angles to the shank and having the reduced end 11 and the opening 12 and adapted to enter the recess *f* in the side of the shuttle and form the delivery eye of the shuttle, as described.

In testimony whereof I have signed my name to this specification in the presence of two subscribing witnesses.

SUMNER A. DUDLEY.
